SWITCH-TYPE PLUG ATTACHMENT
DEVICEJoseph D. Brown, New York, N. Y., assignor to
Raylite Trading Company, Inc., a corporation
of New York

Application March 6, 1934, Serial No. 714,246

8 Claims. (CL. 200—51)

This invention relates to switch-type of plug attachment devices for connecting conductor wire cords to portable electric appliances.

Among the objects of the invention is to generally improve devices of the character described whereby few and simple parts are arranged and constructed to provide a compact, rugged assembly capable of withstanding rough usage, which shall be inexpensive to manufacture yet form a neat appearing structure, and which shall be practical and convenient to a high degree in use.

Other objects of this invention will in part be obvious and in part hereinafter pointed out.

The invention accordingly consists in the feature of construction, combinations of elements and arrangement of parts which will be exemplified in the construction hereinafter described and of which the scope of application will be indicated in the following claims.

In the accompanying drawing, in which is shown various possible illustrative embodiments of this invention:

Fig. 1 is a front elevational view of an electric switch-type of plug attachment device showing the top member of the casing removed to expose the interior construction and assembly.

Figs. 2 and 3 are front and side elevational views of the improved device.

Figs. 4 and 5 are cross sectional views taken on lines 4—4 and 5—5 in Figs. 1 and 2, respectively.

Fig. 6 is a perspective view of the switch current carrying strip having spring contact jaws removed from the device, and

Fig. 7 is a perspective view of the rotary element removed from the casing.

Referring in detail to the drawing, 10 denotes a switch-type plug attachment device constructed to embody the invention. As here shown, said device 10 includes a casing, having a top and bottom member, or mating halves 11 and 12, respectively, which may be formed of a suitable insulating material, such as a molded phenol condensate product. Said halves 11 and 12 are held together by any conventional fastening means, as for example, by spaced screws 13 which may be located to extend through the casing members 11 and 12, as is shown in Figs. 1 and 2.

The inner side of said member 11 and 12, that is, the sides that are brought in face to face relation when assembling the device 10, are each formed with cavities which register to provide suitable chambers for housing the movable parts of the switch mechanism and for retaining the

live current carrying parts enclosed as herein-after described. Thus between the casing members 11 and 12 there is provided parallelly aligned spaced chambers 14 and 15 wherein spring gripping contacts 16 and 17, respectively, are retained.

If desired, these contacts 16 and 17 may be anchored to the casing bottom member 12 by any suitable means such as drive screws 18 extending through the inner ends of said contacts. 10 To give access to said contacts 16 and 17, passages 14a and 15a, respectively, are provided, wherethrough the usual spaced prongs or terminal posts of an electric appliance (not shown) are inserted into the forward or leading end of 15 the casing for connecting such appliance to a suitable power source through the device 10 in the well understood manner. The drive screw 18 extending through the inner end of the spring contact 17 may also serve as fastening means for 20 electrically connecting thereto a front end 19a of a saddle jumper 19.

A rear end 19b of the jumper 19 may be anchored by a drive screw 20 to the casing bottom member 12, said end 19b being provided with an extension terminal screw binding post 19c. 25

The drive screw 18 extending through the inner end of the spring contact 16 may also serve as a fastening means for electrically connecting thereto a front end 21a of a jumper member 21. A rear end of said member 21 forms a lower spring contact jaw 21b of the switch mechanism, the latter being indicated generally at S. An upper spring contact jaw 22b forming an end of a current carrying strip 22 is located in alignment with the lower contact jaw 21b as seen from Figs. 1 and 6. A drive screw 20 may be used to anchor said strip 22 to the casing bottom member 12, said strip 22 being also formed with an extension terminal screw binding post 22a at the end opposite 30 the jaw 22b.

A chamber 23 having an end passage 23a provided within the rear end of the casing gives access to the spaced terminal posts 19c and 22a and encloses a flexible conductor wire cord 24 extending therethrough, the bared ends 24a of said cord being electrically connected to said posts 19c and 22a. The passage 23a may be channelled at 35 23b for retaining therein an enlarged end 25a of a helically coiled armor 25 (only a fragmentary portion being shown) between said casing member 11 and 12, said armor 25 serving in the well understood manner to protect and reinforce the portion of the cord 24 passing into the device 10. 40

The movable parts of the switch mechanism S 55

occupy a chamber 26 formed by cavities in the members 11 and 12 above the chambers 14 and 15. Said moving parts include an element 27 preferably molded of insulating material having 5 a circular shaped top wall 27a which is formed with an arcuate side wall 27b extending partially about the perimeter thereof. Said side wall 27b may be provided at the center of its outer surface with a handle 27c radially extending with respect 10 to said top wall 27a. Said handle 27c may be extended inwardly beyond the inner surface of the said wall 27b to provide a lug 27d for anchoring one end 28a of a tension spring 28, the purpose of which will hereinafter be described. The top 15 and side walls 27a and 27b may be cut away at 27g to facilitate molding and attaching the spring end 28a to the lug 27d which may be pierced to receive said end 28a. Said top wall 27a may also carry the legends "On" and "Off" on the portion 20 thereof bordering the side wall 27b for indicating through an opening 11a in the top member 11 the position of the switch mechanism S. If desired, the top wall 27a may be provided with an integral upstanding central boss or hub 27e concentric positioned with respect to said top wall 27a. Said hub 27e has an opening 27f serving as 25 a bearing for an end 29a of a metallic circuit closer 29.

The member 12 within the chamber 26 is provided with a circular groove 12a which serves as a track in which the end or free edge of the side wall 27b of the element 27 can rotate on moving of the handle 27c. Although the top member 11 may be formed so as to retain the element 27 in 35 place, said element is preferably secured against displacement from its working position on the member 12 by the saddle jumper 19. As shown in the drawing, said jumper 19 is provided with an opening 19c for journalling the hub 27e thereinto to center the element 27 and thereby make the rotary movement smoother.

The circuit closer 29 may be in the form of a U-shaped wire, the mid section 29b of which provides a fastening for the other end 28b of the 45 coil spring 28 as is clearly shown in Fig. 5. The end 29a of the circuit closer 29 which is supported in the bearing opening 27e and the end 29c opposite thereto which is journalled in a recess 12b concentric with the groove 12a and provided in 50 member 12 form a trunnion for the circuit closer 29.

In order to conveniently operate the switch S, the element 27 is positioned so that the handle 27c extends outwardly from the side of the casing 55 through an elongated slot 10a provided in the casing as is shown in the drawing.

The operation of device 10 will now be apparent. With the various parts provided and assembled as described above and shown in the drawing, on 60 moving the handle 27c rearwardly causes the circuit closer 29 to take the "On" position, that is, bridging the spring contact jaws 21b and 22b for closing the circuit passing from strip 22 to jumper 21 and to contact 16, as shown in Fig. 1. 65

On moving the handle 27c forwardly from the "On" position, the element 27 is rotated and since the spring 28 is in tension, the circuit closer 29 remains in the circuit closing position until 70 the handle 27c passes beyond the dead center line indicated by X—X in Fig. 1, thereafter tension by the spring 28 is exerted to snap the circuit closer 29 away from the jaws 21b and 22b for opening the circuit therebetween. The circuit closer 29 will then swing to the position indicated 75

by the dot and dash lines in Fig. 1, and the handle 27c to "Off" position shown in Fig. 2.

Similarly the circuit closer 29 will remain in the "Off" position and will snap into the "On" position on moving the handle 27c rearwardly beyond the dead center line X—X. 5

The "On" and "Off" positions are readily ascertained on sight at either the slot 10a above and below the handle 27c, as shown in Fig. 3, or at the opening 11a on member 11, as shown in Fig. 2. 10

It will thus be seen that there is provided a device whereby the several objects of this invention are achieved and which is well adapted to meet the conditions of practical use.

As various possible embodiments might be 15 made of the above invention, and as various changes might be made in the embodiment above set forth, it is to be understood that all matter herein set forth or shown in the accompanying drawing is to be interpreted as illustrative and 20 not in a limiting sense.

Having thus described my invention, I claim as new and desire to secure by Letters Patent:

1. In a switch-type plug attachment, an insulating case having a circular groove and a recess concentric with said groove, an element having a curved edge wall fitted to rotate in said groove and an opening concentric with said wall, a circuit closer having trunnion portions journaled in said opening and recess, and a spring 25 mounted between an end of said closer and a part of said element at a spaced distance from the opening thereof.

2. In a device of the character described, mating insulating members having cavities in 35 register to form a casing with chambers, a switch mechanism assembly in one of said chambers, said assembly including an insulating element having a circular shaped top wall, an arcuate side wall extending partially about the perimeter of said top wall, and a handle extending outwardly from the side wall radially with respect to said top wall, one of said members having a circular-shaped groove to serve as a track for the free edge of said side wall to ride in, said top 45 wall and the last mentioned member each having an opening, a U-shaped circuit closer provided with out-turned ends journalled in said openings, and a coil spring having one end anchored to the mid portion of said closer and the other end to 50 the side wall of said element.

3. A switch element comprising molded insulated body formed with a circular shaped top wall, an arcuate side wall extending partially about the perimeter of said top wall, and a handle extending outwardly from the mid portion of the side wall and radially with respect to said top wall.

4. A switch element comprising molded insulated body formed with a circular-shaped top 60 wall, an arcuate side wall extending partially about the perimeter of said top wall, a handle extending outwardly from the mid portion of the side wall and radially with respect to said top wall, and a lug extending from the inner surface 65 of the side wall as and for the purpose described and specified.

5. A switch element comprising molded insulated body formed with a circular-shaped top wall, an arcuate side wall extending partially 70 about the perimeter of said top wall, a handle extending outwardly from the mid portion of the side wall and radially with respect to said top wall, and a lug extending from the inner surface 75 of the side wall as and for the purpose described 75

and specified, a portion of said element being cut away to give access to said lug.

5. A switch element comprising molded insulated body formed with a circular shaped top wall, an arcuate side wall extending partially about the perimeter of said top wall, a handle extending outwardly from the mid portion of the side wall and radially with respect to said top wall, a lug extending from the inner surface of the side wall as and for the purpose described and specified, a portion of said element being cut away to give access to said lug, and indicating legends on the top and side walls.

10. A switch element comprising molded insulated body formed with a circular shaped top wall, an arcuate side wall extending partially about the perimeter of said top wall, and a handle extending from the mid portion of the side wall and radially with respect to said top wall, and

indicating legend on the top wall bordering the side wall.

15. In a switch-type plug attachment, an insulating casing having a top and bottom member, the bottom member having a circular groove and a recess concentric with said groove, an element enclosed in the casing having a circular top wall, a curved side wall extending from said top wall fitted to rotate in said groove and an opening concentric with said top wall, indicating 5 switch-position legends on the top wall bordering the side wall, said top member having a window in register with one of said legends, a circuit closer having trunnion portions journaled in said opening and recess, and a spring mounted 10 between an end of said closer and a part of said element at a spaced distance from the opening thereof.

JOSEPH D. BROWN.
